RELAY

Anthony I. Kasper, Schenectady, N. Y., assignor
to General Electric Company, a corporation
of New York

Application February 20, 1941, Serial No. 379,844

4 Claims. (Cl. 200—97)

This invention relates to relays and more particularly to improvements in electromechanical primary relays for automatic regulators.

In order for an automatic electrical regulator to maintain the regulated quantity substantially constant, it is necessary that it be controlled by a sensitive primary electroresponsive device. Many of these devices are electromagnetically-operated contact-making devices which in order to be sufficiently sensitive must be constructed with practically the same care and precision as is employed in the construction of sensitive electric meters. The moving parts must be light in weight and small in size and consequently the contacts which are directly actuated by the device are often not suitable for controlling the current necessary for operating the regulator, or operating the driving motor with which many automatic regulators are provided. It is, therefore, customary to employ an auxiliary relay having a relatively low input which can safely be handled by the contacts of the primary relay and having relatively rugged contacts which are capable of handling the current of the operating motor. Furthermore, in many automatic regulators it is desirable to provide a definite time delay between the response of the primary relay and the operation of the regulator in order to prevent unnecessary operation of the regulator in response to momentary deviations of the regulated quantity from its normal value. This time delay is usually provided by means of a separate time delay relay.

In accordance with this invention there is provided a novel electromechanical relay which combines in one unit the functions of the primary relay, the auxiliary relay and the time delay relay. It is characterized by relatively high sensitivity, the absence of any vibrating or trembling engagement of contacts and the separate adjustability of the lengths of the time delay interposed in the raising and lowering actions, respectively, of the regulator.

An object of the invention is to provide a new and improved electromechanical relay.

Another object of the invention is to provide a sensitive time delay relay which is capable of handling directly the relatively large amounts of current required by the operating motor of motor-operated automatic regulators.

The invention will be better understood from the following description taken in connection with the accompanying drawing and its scope will be pointed out in the appended claims.

In the drawing Fig. 1 is a perspective view of

the mechanism included in an embodiment of the invention and Fig. 2 is a circuit diagram of the electrical connections of the invention when it is used in an automatic rheostatic generator voltage regulating system.

Referring now to the drawing, and more particularly to Fig. 1, the primary electroresponsive device consists of a solenoid magnet 1 mechanically connected by means of a wire 2 to a pivotally mounted lever system 3. The pivotal mounting is a so-called cross-spring mounting consisting of a pair of vertical blade springs 4 and a pair of horizontal blade springs 5 (only one of which is visible) interconnecting a rigid support 6 and a movable piece 7 forming part of the lever system. The effective pivot of this arrangement is along the imaginary line formed by the intersection of the substantially perpendicular planes in which the springs 4 and 5 lie. Attached to the piece 7 is a movable arm 8 whose lower end is bent outwardly at right angles to form a stop for a blade spring 9 carrying at its outer end an H-shaped piece 10. The pull of the magnet 1 is counterbalanced by an adjustable weight 11 and the position of the entire lever assembly is biased toward a neutral or normal position by means of a permanent magnet 12 which is adjustably positioned with respect to pole pieces 13 by means of a slot and eccentric arrangement 14 operated by a thumb screw 15. The pole pieces 13 cooperate with a U-shaped magnetic member 16 carried by the lever assembly.

The position of the weight 11 is determined by the desired normal value of the regulated quantity, in proportion to which the magnet 1 is energized, its location being such that the entire assembly is balanced when the magnet is normally energized. The pole pieces 13 are so located that they tend to hold the normally balanced lever assembly in a normal or neutral position. This position is characterized by the H-shaped piece 10 being midway between the arms of a U-shaped member 17 which is continuously reciprocated by a cam 18 on a cam shaft 19 which is continuously driven in the same direction by means of a motor 20. The cam 18 is preferably made of fibre rather than metal so as to provide quiet operation and the U-shaped member 17 carries a roller type cam follower 21 for reducing wear and friction. The member 17 is supported in any suitable manner so as to confine its motion to the vertical. For example, it may be supported by means of a flat blade spring assembly, the outer end of which is shown at 22. The main control contacts of the device are

shown as separate pairs of normally open contacts 23 and 24, contacts 23 being the raise contacts and contacts 24 being the lower contacts. Each of the contacts is mounted on its own blade spring, the motion of the inner contact of each pair being limited in the outward direction by means of rigid stops 25. The contacts are actuated by pivotally-mounted yoke-shaped members 26 having downward extensions 27. The arrangement is such that when the downward extensions are moved outwardly from the center of the device (the center being defined generally by the vertical portion of the movable arm 8) the outer ones of the sets of contacts will be moved inwardly into engagement with their respective companion contacts. As all of the contacts are spring mounted the contacts can move together after they come into engagement so that a considerable amount of additional outward motion of the extensions 27 is permitted after the contacts do engage each other. On the return or inward motion of the extensions 27 the contacts will stay together until the springs carrying the inner contacts engage the stops 25 whereupon a relatively quick break of the contacts is effected.

The time delayed closing of the separate sets of contacts in response to movement of the lever assembly of the primary electroresponsive device away from its neutral position is accomplished by means of complementary ratchet mechanisms 28 and 29, the former operating the raise contacts 23 and the latter operating the lower contacts 24. These mechanisms are substantial duplicates, except that they have a right hand to left hand relation, and consequently their corresponding parts are given the same reference numbers. They each consist of a ratchet wheel 30 mounted for rotation on a shaft 31. For the purpose of permitting adjustment of the time delay, each wheel consists of two adjacent relatively rotatable gears 32 and 33, 32 being the inner wheel and 33 being the outer wheel, as viewed in the drawing. These two wheels are normally locked against relative rotation by means of a pinion gear 34 which is as wide as the two gears together and which consequently permits their rotation as a unit while preventing their rotation relative to each other.

For rotating each wheel 30 in the direction for causing closure of its associated set of contacts there is provided a pawl 35 pivotally mounted on a shaft 36 carried in a cage or frame 37 which is itself pivotally mounted on the shaft 31. Similarly, for rotating each wheel 30 in the opposite direction for causing opening of its associated set of contacts there is provided an opening pawl 38 pivotally mounted on a shaft 39 carried in a frame 40 which is also pivotally mounted on shaft 31. For operating each of the switches there is provided a pin 41 set into the inner face of the wheel 32 and so located that it will engage the downward extension 27 of the switch operating yoke 26. For preventing continued rotation of each ratchet wheel after its respective switch has been closed there is provided a pin 42 for engaging a backwardly and inwardly extending arm 43 on the closing pawl 35. This engagement in turn prevents the pawl from engaging the teeth of the ratchet wheel.

For operating the opening pawl 38 so as to rotate these ratchet wheels 30 in the direction for opening their associated sets of contacts there are provided frames 44 pivotally mounted on the shafts 31. These frames are provided respec-

tively with inwardly extending arms 45 and 46, each of which is provided at its extremity with a cam follower for engaging respectively a cam 47 and a cam 48 mounted on the cam shaft 19. For preventing each opening or resetting pawl 38 from continuing to rotate its wheel 30 beyond a definite angular position there is provided a pin 49 set into the face of the outer half 33 of the ratchet wheel. This pin engages an inwardly projecting arm 50 on the frame 44, thus pivoting the frame 44 about the shaft 31 in such a direction as to prevent the cam 47 or 48, as the case may be, from engaging its associated cam follower.

In order to prevent locking of the mechanism by the simultaneous operation of the pawls 35 and 38 the frame 37 is provided with a gear segment 51 for engaging a pinion gear 52 mounted on a spur shaft 53 to which is attached a cam or trigger member 54 which is arranged so as to engage the extremity of an inwardly extending arm 55 on a lever 56 carried by the opening pawl 38.

Adjustment of the amount of time delay is made possible by means of a rotatable knob 57 mounted on the same shaft which supports the gear 34, this shaft being provided with an enlarged outer head against which an inner shoulder in the knob 57 is pressed by means of a spring 58 on the inside of the gear 34. The knob is larger in diameter than the gear 34 but has a flattened portion which will permit the knob to be pushed inwardly when this portion faces the teeth of the ratchet wheel. The knob 57 also carries a pin 59 for entering a hole 60 in the outer face of the outer ratchet section 33. When the gear is rotated so that the hole 60 is opposite the pin 59, which is the position shown for the operating mechanism for the raising contacts 23, the knob 57 may be pushed inwardly. This locks the outer part 33 of the ratchet wheel from rotation and at the same time it unlocks the parts 32 and 33 because the gear 34 is pushed inwardly ahead of the knob 57 so that it disengages the teeth of the outer wheel 33. The inner wheel 32 may then be rotated in either direction so as to change the angular relation between the pin 49 on the one hand and the pins 41 and 42 on the other hand. This angular relation is indicated in terms of seconds of time delay by a scale on the inner wheel 32 which is visible through a window in the wheel 33 and which scale cooperates with an index point on the wheel 33.

The operation of the illustrated embodiment of the invention is as follows: As shown, the lower contacts 24 are closed and the raise contacts 23 are open and the block 10 has been moved to the left of its neutral position, thus indicating that the energization of the magnet 1 is below normal. In other words, the position of the parts indicates that the mechanism as a whole has just responded to a decrease below normal of the regulated quantity following an extended period in which the quantity was above normal. Assume now that the motor 20 is rotating continuously. Its direction of rotation is immaterial and we will assume, for example, that it is rotating in a clockwise direction. This will cause the two ratchet wheels 30 to be rotated simultaneously step by step in a counterclockwise direction, as viewed in the drawing. The rotation of the right hand ratchet wheel 30 is accomplished by means of the cam 48 which causes reciprocating motion of the frame 44

whereby the left hand end of this frame engages the outer end of the pawl 38 on each up stroke, thereby pivoting the pawl about the shaft 39, causing it to engage the teeth of the gear 30 and rotate this gear one notch or step for each revolution of the cam 48. This will almost immediately cause the pin 41 to disengage the extension 27 of the operating member for the contacts 24 thereby opening these contacts. However, the step by step counterclockwise rotation will continue until the pin 49 engages the extension 56 of the frame 44 and raises it high enough to prevent the cam 48 from reciprocating its associated cam follower.

At the same time that this is taking place the closing pawl 35 of the mechanism 28 for the raising contacts 23 is being reciprocated by means of the left hand arm of the U-shaped member 17 engaging the block 10 and pushing it upwardly into engagement with the pawl 35 during each up stroke of the member 17. The closing pawl 35 pivots about its shaft 36 until its pivoting motion is limited by the opening in the frame 37 through which it extends whereupon the entire frame and pawl are lifted as a unit thereby rotating its associated wheel 30 one step. At the same time that the frame 37 is lifted the tripping arm 54 is raised by means of the segment 51 and gear 52 until it engages the extension 55 of the arm 56 carried by the pawl 38. The frame 44 is being held out of engagement by the cam 47 by means of the pin 49 which through the arm 50 has raised the frame 44. However, as soon as the gear 30 starts rotating in the counterclockwise direction the pin 49 permits the frame 44 to move downwardly so that the cam follower on its arm 45 will be engaged by the cam 47. However, the resulting reciprocating motion of the frame 44 does not cause the pawl 38 to engage the teeth of the gear 30 because of the operation of the arm 54 in simultaneously raising the inner end of the opening pawl 38 through the extension 56. Consequently, the ratchet wheel 30 continues to rotate in the counterclockwise direction until pins 41 and 42 engage arms 27 and 43, respectively. The engagement of pin 41 and arm 27 causes closure of the raising contacts 23 in the manner previously described while engagement of the pin 42 and the arm 43 locks the closing pawl 35 out of engagement with the teeth of the ratchet wheel 30 so that continued reciprocation of the outer end of the closing pawl 35 will merely reciprocate the frame 37 without causing further ratcheting of the wheel 30.

If the block 10 is now returned to its neutral position the arms 17 of the U-shaped member will slide up and down on opposite sides of the block 10 without reciprocating this block and consequently arm 54 will no longer be actuated so that the reciprocating motion of the frame 54 will then cause the opening pawl 38 to engage the teeth of the ratchet wheel 30 and turn it step by step in the clockwise direction so as substantially immediately to open the raise contacts 23. This action will continue in the manner previously described for the operating mechanism 29 for the lower contacts until the pin 49 again engages the arm 50 and raises the frame 44 so as to cause the arm 45 to remove its cam follower from the cam 47.

Similarly, if the block 10 should be moved to the right of its neutral position indicating that the energization of the magnet 1 is above normal the closing pawl 35 of the right hand mechanism will be operated so as to rotate the ratchet wheel

30 step by step in a clockwise direction in the same manner as has been previously described for the left hand mechanism.

From the above description it will be seen that the operating mechanisms are in a sense lost motion connections between the motor or the means reciprocated thereby and the contacts because it requires a considerable amount of motion or rotation of each of the mechanisms from their initial or reset positions until the mechanical connection is made by means of the pins 41 to the switch operating means for closing the separate sets of contacts.

If desired, the ends of the arms of the member 17 may be beveled, as shown, so that the greater the movement of the block 10 away from its neutral position corresponding to greater departures from normal of the condition to be regulated, the higher the block 10 will be raised on each up stroke of the member 17. This will mean a greater angular rotation of the ratchet wheels for each step of rotation and consequently it will mean a shorter time delay. In other words, by means of such beveling the time delay may be made to vary inversely with the degree of the departure from normal of the regulated quantity.

In Fig. 2 the operating magnet 1 is shown connected across the terminals of a direct current generator 61 whose voltage is to be varied by means of a motor-operated rheostat 62 which controls the field current of the generator. The direction of operation of the motor is selectively controlled by the contacts 23 and 24. In this manner when the voltage is normal the motor is at rest but if the voltage departs from normal the contacts 23 and 24 will close after appropriate time delays depending upon whether the voltage has risen above or fallen below normal whereupon the motor 62 will rotate in the proper direction to cause the rheostat to restore the voltage to normal. While for the sake of simplicity I have shown my invention in connection with a motor-operated generator voltage regulator, it will be obvious to those skilled in the art that the motor for the motor-operated rheostat 62 could equally well be made to drive any other well-known form of regulator, such as a transformer regulator of either the induction or step types.

While there has been shown and described a particular embodiment of this invention, it will be obvious to those skilled in the art that various changes and modifications can be made therein without departing from the invention, and, therefore, it is aimed in the appended claims to cover all such changes and modifications as fall within the true spirit and scope of the invention.

What I claim as new and desire to secure by Letters Patent of the United States is:

1. In combination, an electroresponsive device having a movable member, a continuously operating motor, a two position circuit controller, a lost motion coupling having a driven element for moving said circuit controller from one position to the other, a driving element for said coupling, and means under the control of said movable member for selectively operating said driving element in either direction by means of said motor.

2. In combination, two pairs of normally open contacts, an electroresponsive device having a movable member whose position is determined by the degree of energization of said device, said member having a normal position corresponding to a normal energization of said device, an ir-

reversible continuously operating motor, wholly mechanical means responsive to displacement of said member from said normal position in one direction for causing said motor to close one of said sets of contacts after a predetermined time delay, wholly mechanical means responsive to displacement of said member from said normal position in the other direction for causing said motor to close the other set of contacts after a predetermined time delay, and wholly mechanical means for reopening either set of contacts when said member is returned to its normal position.

3. In combination, two pairs of normally open contacts, an electroresponsive device having a movable member whose position is determined by the degree of energization of said device, said member having a normal position corresponding to a normal energization of said device, an irreversible continuously operating motor, wholly mechanical means responsive to displacement of said member from said normal position in one direction for causing said motor to close one of said sets of contacts after a predetermined time delay, wholly mechanical means responsive to displacement of said member from said normal position in the other direction for causing said motor to close the other set of contacts after a predetermined time delay, wholly mechanical means for reopening either set of contacts when said member is returned to its normal position, and separate means for independently adjusting the lengths of said time delays.

4. In combination, an electroresponsive device having a movable member whose position is determined by the degree of energization of said device, a continuously operating source of reciprocating motion, a ratchet wheel, a first pawl, said movable member serving in one position thereof to connect said first pawl to said source of reciprocating motion and in another position to disconnect said first pawl from said source of reciprocating motion, said first pawl when connected to said source of reciprocating motion acting to rotate said ratchet wheel step by step in one direction, a circuit controller, means for changing an electrical property of said circuit controller when said wheel reaches a given angular position, means for preventing said pawl from engaging said ratchet wheel when said angular position is reached, a second pawl for rotating said wheel step by step in the opposite direction, means for connecting said second pawl to said source of reciprocating motion, means for preventing said second pawl from engaging said wheel while said first pawl is reciprocating and for permitting said second pawl to engage said wheel when said first pawl is stationary, and means for disconnecting said second pawl from said source of reciprocating motion when said wheel reaches a second given angular position.
